(57) **CLAIM**

The ornamental design for a male penile stimulation device, as shown and described.

DESCRIPTION

FIG. 1 is a rear, top, right side perspective view of our new design, showing the design in a storage position;

FIG. 2 is a rear side view of the design in the storage position;

FIG. 3 is a front side view of the design in the storage position;

FIG. 4 is a left side view of the design in the storage position;

FIG. 5 is a right side view of the design in the storage position;

FIG. 6 is a top view of the design in the storage position;

FIG. 7 is a bottom view of the design in the storage position;

FIG. 8 is a rear, top, right side perspective view of the design, showing the design in a use position;

FIG. 9 is a rear side view of the design in the use position;

FIG. 10 is a front side view of the design in the use position;

FIG. 11 is a left side view of the design in the use position;

FIG. 12 is a right side view of the design in the use position;

FIG. 13 is a top view of the design in the storage use; and,

FIG. 14 is a bottom view of the design in the use position. The features shown in broken lines in the drawing views are for illustrative purposes only and do not form part of the claimed design.

1 Claim, 14 Drawing Sheets
